CLAIM

The ornamental design for a window for vehicle, as shown and described.

DESCRIPTION

FIG. 1 is a perspective view of a window for vehicle, showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

A mirror image of the window for vehicle of FIGS. 1-7 being a second embodiment of the window for vehicle.

1 Claim, 4 Drawing Sheets(56)
